REVOLVER GRIP

George W. Wylie, Gary, Ind.

Application October 11, 1948, Serial No. 53,900

4 Claims. (Cl. 42—71)

1

This invention relates generally to firearms, and more particularly is directed to handle grips for a revolver.

Revolvers are standard equipment for policemen, mail train clerks, peace officers, and others acting in an official capacity. Additional cartridges for use are generally carried in a belt constituting a part of such equipment.

Anyone having experience in the use of revolvers appreciates the inconvenience of locating the cartridges in a belt and withdrawing them, particularly when they have remained in the belt for a considerable period and become stuck or frozen. Practically every police officer at one time or another has been placed at a serious disadvantage during an emergency due to the difficulty in withdrawing cartridges from the belt. During the winter months, heavy outer wearing apparel interferes with quick access to the belt and a glove or mitten must be removed before the cartridges can be forced upwardly through the loops of the belt.

It is the common practice among police officers to apprehend an escaping suspect by the firing of warning shots over his head. This act may deplete the immediate supply of cartridges in the cylinder to an extent whereby the suspect may be the aggressor, thereby endangering the life of the officer, particularly during a reloading period.

Accordingly, one of the principal objects of the subject invention is to overcome the disadvantages above referred to and provide an additional supply of cartridges, which will be readily available for instant use in any emergency.

More particularly in this respect, an object of the invention is to provide handle grips for a revolver with chambers for receiving an additional supply of cartridges.

An important object of the invention is to provide means for normally retaining the cartridges in the chambers and a lock or latch for such means.

A particular object of the invention is to preferably design and construct the retaining means in the form of a pivotal cover and arrange the chambers longitudinally with respect to the revolver butt so that when the cover is unlocked and tilted at an appropriate angle the cartridges will fall out and be deflected by the cover into

2

the palm of the hand for instant use in reloading the cylinder.

Another object of the invention is to provide an improved latch for the cover which is conveniently located for operation.

A further object of the invention is to provide resilient means, whereby, if desired, the cartridges may be ejected automatically upon releasing the latch.

10 A still further object is to provide a plate which preferably serves to reinforce and connect the grips at their outer extremities and at the same time provides a support for the cover and latch.

Additional objects reside in the simplicity of 15 design and construction of the grips to facilitate their attachment to the conventional revolver butt frame; increased gripping area over the conventional grips; lightness in weight; durability; and economy of manufacture.

20 Other objects and advantages of the invention will become apparent after the description hereinafter set forth is considered in conjunction with the drawing annexed hereto.

In the drawing the preferred form of the invention is illustrated, and for convenience, like parts are designated by the same numeral.

Figure 1 is a side view, in elevation, of a conventional revolver illustrating the invention applied thereto and the position of cartridges escaping from the handle grips;

Figure 2 is a partial enlarged vertical section taken through an appropriate part of the butt structure depicting details of the reinforcing plate, cover, and latch means;

35 Figure 3 is a bottom view of the revolver butt structure looking in the direction of the arrows 3—3 in Figure 2;

Figure 4 is a transverse section taken substantially on line 4—4 of Figure 3 illustrating 40 other constructional details of the plate, cover, and latch; and

Figure 5 is a transverse section taken substantially on line 5—5 of Figure 3 depicting the relationship of certain of the parts.

45 The revolver exemplified in Figure 1 is of the conventional type and, among other things, includes a butt frame 1, and a cylinder 2 capable of holding a plurality of cartridges. Handle grips 3 and related structure comprising the subject invention are adapted to be substituted for

50

those of the conventional form and are secured to the inner part of the frame 1 by fastening means 4. The grips 3 are substantially identical and conform to the general configuration of the frame. They may be made out of any material suitable for the purpose, but are preferably constructed from a durable plastic which is moulded to the shape desired.

The grips 3 are preferably made somewhat thicker and longer than the conventional grips in order that a row of three cylindrical chambers 5 may be provided in each grip for the cartridges. The chambers 5 preferably extend inwardly from the butt end in spaced parallel relation and are of sufficient diameter and length to freely support the cartridges. Due to the moderate increased size of the grips, greater gripping area for the hand is provided.

The grips are preferably connected together adjacent their outer extremities by a plate 6 which abuts the end of frame 1 and ends of the grips. The plate 6 is secured to the grips by screws 7, and is provided with rows of apertures 8 registering with and of a diameter corresponding to that of the chambers 5. This plate, among other things, limits the inward movement of the cartridges.

A cover 9 of a size substantially corresponding to the size of the plate is pivotally connected to the plate by a pivot 10. It is to be noted that the point of connection therebetween is preferably located at the outer extremities of the plate and cover adjacent to the outer edge 11 of the butt frame 1 as illustrated in Figures 1, 2 and 3.

The opposite and inner extremity of the plate 6 is provided with an opening 12 and an adjacent outwardly extending offset or raised portion 13 spaced from and generally parallel with respect to the end surface 14 of the frame 2.

A latch means 15 is disposed for reciprocation in the space between portion 13 and the frame, and includes a generally rectangular base portion 16, an inner angled holding portion 17 extending outwardly from the opening 12, and an outer angled finger portion 18 for manipulating the latch. A clearance recess 19 may be provided in the inner edge 20 of the frame to facilitate operation of the latch. One side of the holding portion is provided with retaining groove 21 designed to detachably receive a detent 22 formed on the cover, and its other side is provided with a recess 23 for receiving the yieldable portion 24 of a generally U-shaped spring. The legs 25 of the spring are caught in holes provided therefor in the grips and plate 6. It will be noted that the detent 22 is preferably formed adjacent the inner marginal edge of a generally square shaped notch 26, the notch providing clearance for the reception of the offset portion 13 of the plate.

The latch is so constructed and arranged that by pulling out on the same as indicated by the dotted lines in Figure 2, it will release the detent 22 from the groove 21, whereupon any cartridges in the chambers 5 will drop out and be deflected by the cover into the palm of the hand for immediate use. The yieldable portion 24 of the spring is of a length to provide sufficient resilience to normally maintain the latch in the holding position as depicted in Figure 2. It is to be understood that insofar as the present invention is concerned, it is immaterial whether the latch mechanism is constructed as exemplified or in any other form. It is also to be understood that if found desirable, the cover may be slid-

ably mounted with holes off center with the chambers so that when the cover is slid to place the holes on center the cartridges will be released therethrough. Moreover, the invention contemplates an assembly wherein the cover may be directly pivoted to the frame 1 whereupon the plate 6 may be omitted, in which the event the outer extremities of the grips would be connected to the frame by fastening means similar to 4.

Attention is directed to the fact that the cover assumes a normally spaced parallel relation with respect to the plate, the purpose of which is to provide clearance for the butt ends or rims of the cartridges which rims engage the plate.

As stated above, one object of the invention is to provide a construction by which the cartridges are automatically ejected when the latch releases the cover. This is accomplished by providing a relatively small hole at the base of each chamber and securing a helical spring 27 therein with one end engaging the cartridge to normally urge it outwardly against the cover.

In view of the foregoing description it will be manifest that improved means are provided whereby an additional supply of cartridges is made readily available for immediate use, thereby affording greater protection for a police officer in order that he may better control the activities of criminals and maintain peace.

Having thus described my invention, it is obvious that various modifications may be made in the same without departing from the spirit of the invention, and, therefore, I do not wish to be understood as limiting myself to the exact forms, constructions, arrangements, and combinations of parts herein shown and described and defined in the claims.

I claim:

1. A pistol butt frame having opposite sides of a width greater than its thickness, a pair of substantially corresponding hand grips secured to the opposite sides of the frame and conforming generally to its configuration, the butt end of each grip having a row of chambers extending inwardly lengthwise of the grip with the rows arranged substantially in parallel relationship, and a cover common to both rows for concealing and detachably holding cartridges placed in the chambers.
2. A pair of moulded generally curved hand grips corresponding substantially in size and shape for attachment to the opposite sides of a pistol butt frame, means carried by the grips for securing them to a frame, the butt end of each grip having a row of chambers extending inwardly lengthwise of the grip so that when the grips are secured to a frame the rows will be disposed in substantially parallel relationship on opposite sides thereof, and a cover common to both rows for concealing and detachably holding cartridges placed in the chambers.
3. A pistol butt frame having opposite sides of a width greater than its thickness, a pair of substantially corresponding hand grips secured to the opposite sides of the frame and conforming generally to its configuration, the butt end of each grip having a row of chambers extending inwardly lengthwise of the grip with the rows arranged substantially in parallel relationship, and cover means for both rows for concealing and detachably holding cartridges placed in the chambers.
4. A pair of hand grips corresponding substantially in size and shape for attachment to the

opposite sides of a pistol butt frame, means carried by the grips for securing them to a frame, the butt end of each grip having a row of chambers extending inwardly lengthwise of the grip so that when the grips are secured to a frame the rows will be disposed in substantially parallel relationship on opposite sides thereof, a bridge member, means for securing the bridge member to the grips, and cover means for both rows carried by said bridge member for concealing and detachably holding cartridges placed in the chambers.

GEORGE W. WYLIE.
